UNITED STATES PATENT OFFICE.

GEORGE L. IRWIN, OF ALLEGHENY, PENNSYLVANIA, ASSIGNOR TO HIMSELF
AND R. L. ORR, OF SAME PLACE.

DRIER FOR WHITE LEAD AND OTHER MATERIALS.

SPECIFICATION forming part of Letters Patent No. 288,574, dated November 13, 1883.

Application filed March 10, 1883. (No model.)

To all whom it may concern:

Be it known that I, GEORGE L. IRWIN, of Allegheny, in the county of Allegheny and State of Pennsylvania, have invented a new 5 and useful Improvement in Driers for White Lead and other Materials; and I do hereby declare the following to be a full, clear, and exact description thereof.

My invention relates to the drying of white lead or other pulverulent or granular substances or materials, and has special reference to the drying of white lead during its treatment for the manufacture of paint. After the lead has been corroded, it is first crushed and 15 then ground with water, to wash out the acid, and the water is then thoroughly dried out before it is chased in oil, and ground in oil to form the finished product. The only method of drying the lead heretofore generally employed is to spread it over large flat steam-heated pans, each pan holding about five tons of lead, and gradually dry out the moisture, the operation requiring seven or eight days, and the steam-heat being necessarily kept up 25 day and night. These drying-pans are exceedingly expensive, and in an ordinary lead-works from six to twelve of these pans are required, and the time lost in drying the lead adds largely to the expense of manufacture. 30 It is also found that the lead cakes and forms lumps when drying, and for this reason it is necessary to chase the lead in oil before it is mixed and ground for use. For these reasons an efficient and more rapid means of drying 35 the lead is much sought for; and the special object of my invention is to supply this need, though my improved drying apparatus may be employed for drying many other pulverulent or granular materials.

My invention consists, essentially, in the combination of a hollow heated trough or pan, a hollow heated pipe rotated therein, and provided with a flight or equivalent means for feeding the materials to be dried through the 45 trough, and hollow heated rolls for crushing and pulverizing the material during drying, so that the lead is confined between the heated surfaces of the trough and pipe, and the moisture gradually driven off, the lead being fed 50 forward in the trough and crushed and pulverized as it is delivered from the drying ap-

paratus, and the process of drying being continuous.

It also consists in combining with two or more of these troughs and pipes heated rolls, 55 located so as to receive the material from one trough and deliver it to the one below.

It also consists in certain improvements in the construction of the heated trough and pipe, the flight or feeding apparatus, and the hollow 60 heated rolls and their steam-connections.

To enable others skilled in the art to make and use my invention, I will describe its construction and operation, referring to the accompanying drawings, in which—

Figure 1 is a side view, partly broken-away, of my improved apparatus. Fig. 2 is a top view of the drying-trough and pipe, the wing-flanges of the trough being removed. Fig. 3 is a cross-section of the drying-trough and 70 pipe. Fig. 4 is a top view, partly broken away, of the crushing-rolls; and Fig. 5 is a longitudinal section of one of the crushing-rolls.

Like letters of reference indicate like parts 75 in each.

The apparatus is supported in the framework A, which is preferably formed of heavy vertical standards at each end, connected by cross-braces a, on which the troughs or pans 80 B and the housings c of the crushing-rolls C are supported.

The trough or pan B is formed of a cast-iron box, b, and is generally about twenty-five feet long. The upper faces of the end plates 85 of the box are semicircular, and the box is covered by the plate d, thus forming the semi-cylindrical trough or pan within which the tube E is rotated. The plate d is secured to the box by the bolts d' passing through the flanges 90 b' of the box b, and by riveting at the ends of the box, the pan being formed steam-tight.

The pipe or tube E is slightly smaller in diameter than the trough portion of the pan, and is provided with the worm, flight, or other 95 apparatus for conveying the material along the trough, the apparatus preferred by me being the worm or flight e, which extends out from the pipe E and fits the trough portion of the pan neatly.

As it is necessary that the material to be dried be held in close contact with the heated

surfaces of the drying apparatus, the flight *e* is shallow, being generally made about one-half inch high. To hold the material within the trough, the pan is provided with the curved supplemental wing-flanges *F*, which fit closely to the flight *e* for a short distance, and then extend above the flight, the flanges being drawn together to preclude the escape of any material, and yet leave a space above for the escape of the steam evaporated from the material to be dried. The flanges *F* are secured to the braces *f*, and are secured to the trough by means of the bolts *d'*, which extend through the braces, flange-plates, trough-plate, flanges *b'* of the box *b*, securing them all firmly together, as shown in Fig. 3.

The flight *e* extends spirally around the pipe *E*, being either continuous or sectional, as desired, and as the pipe is rotated the flight feeds the lead or other material longitudinally along the trough between the heated pan and pipe. As some of the material may dry into lumps and travel up the flight, I form, at intervals, on the flight the wings *g*, which extend out therefrom along the pipe *E* in substantially a longitudinal direction, the wings being the same height as the flight at the rear and for a short distance therefrom, and then gradually decreasing in height until they vanish at or near the next turn of the flight, and these wings will lift the lumps of lead or other material and carry them over the pipe, so that they necessarily pass between the heated faces of the trough and pipe. These wings *g* are made the same height as the flight for but part of the length, because they are only designed to lift the lumps which gather along the flight and run up it, and are not carried forward thereby. By causing them to pass between the heated faces of the trough and pipe they are more rapidly dried, and thus fall apart.

The working-faces of the trough, pipe, and flight are preferably made of copper when used for drying lead; but for drying other materials, iron, steel, or other metal may be employed, according to the materials to be dried.

Steam is conducted to the trough-pan *B* for heating it through the pipe *b'* at one end thereof, and the water of condensation and exhaust-steam passes out of the pan through the pipe *b'* in the base of the pan at the opposite end, and from thence into the exhaust-pipe *s*. The pipe *E* is journaled in suitable bearings in the frame *A*, and is rotated by means of the pulley *h*, power being communicated from one pipe to another, where more than one are used, through the gear-wheels *h'*. The steam passes into the pipes *E* from the pipes *k* at one end of the apparatus, being connected thereto by the swivel *k'*, and it exhausts into the pipes *l* at the other end through the swivel *l'*.

The supply-pipes *k* may be of any suitable size; but the exhaust-pipes *l* and their swivels must be of the same or greater interior diameter than that of the pipes, to carry away all water of condensation, this being absolutely

necessary, because the water would chill the lower face of the pipe, which comes in contact with the material to be dried, and should be kept at as high a heat as possible.

In order to crush any lumps in the material as it is fed to the different pans, and finally from the apparatus, I employ the hollow rolls *C*, heated by steam or in other manner. The rolls are mounted in housings *c*, supported on the cross-braces *a* in such position as to receive the material from the vat or from the drying-pan, crush it, and deliver it into the pan below, any suitable chutes or guides being employed to direct the materials into the rolls and pans. As the rolls are most efficiently heated by steam, I have illustrated the power and steam connections, their construction being particularly shown in Figs. 4 and 5. As the crushing-pressure on the rolls is slight, and they are required to be thin to permit the rapid passage of the heat from the steam, they are preferably formed of wrought metal, copper being usually employed, or the rolls having a sheathing of copper when employed with lead-drying apparatus. The rolls are journaled in the housings at their full diameter, and at one end are the necks *m*, carrying the band-pulleys or gear *n*, by which power is applied to the rolls. Beyond the pulleys are the swivels *t*, by which the steam-connections are made between the supply-steam pipe and the rolls. The other or exhaust ends of the rolls are connected by the swivels *r* with the steam-boxes *R* in such manner that the interior face of the rolls and steam-boxes are even, so that all water of condensation can pass out of the rolls into the steam-box *R*, and from the steam-box into the exhaust-pipe *s*, so that the rolls are not chilled thereby. I prefer to employ a pair of these heated rolls at the feeding end of the apparatus, to insure the crushing of all lumps of material to be dried, as it dries more quickly when in a pulverulent or finely-divided condition, and at the discharge end to crush any lumps which may have formed in drying.

The exact construction and arrangement of the different parts of the apparatus may, of course, be changed according to the material to be dried or location of the apparatus.

In drying lead by my improved apparatus I prefer to employ three or more of the drying-pans. The pans *B*, pipes *E*, and rolls *C* are heated by the steam passing through them, and the pipes and rolls are rotated at a slow speed. The lead is fed from the vat through the rolls *C* above the first pan, and, after being crushed thereby, passes into the trough of the pan *B*. As the flight *e* on the pipe *E* catches the lead it draws it forward in the trough, and as the lead is confined between the heated surfaces of the pan and pipe the moisture is gradually dried out of it, the steam and moisture passing out through the space between the wing-flanges *F* of the pan, and these flanges holding the lead within the trough of the pan. The flight on the pipe keeps the

particles of lead in motion, turning it over, so that it is all brought into contact with the steam-heated surfaces of the pipe and pan. In case the lead forms into lumps in drying, these lumps have a tendency to run up the face of the flight without being fed forward thereby, and the wing *g* on the pipe then carries over these lumps, causing them to pass under between the pipe and trough in the hottest part of the trough, so that the moisture contained in them is dried out, and when dry the lumps will break up, and so be carried forward by the flight on the pipe. As the wings only extend to the height of the flight at the rear, they are only adapted to carry over the lumps, allowing the flight to carry the particles of lead forward in the usual manner. The lead is thus carried forward between the heated surfaces of the pan and pipe until it reaches the discharge end of the trough, from which it passes through the crushing-rolls *C* into the next pan, any lumps formed being crushed, and the material being delivered thereto in a pulverized or finely-divided form. It is thus carried through as many pans as desired until it is thoroughly dried, and finally crushed as it leaves the last pan, and is delivered to the proper bin or receptacle for grinding.

As the lead is kept in motion during the entire time of drying, and is prevented from caking or forming into lumps, as before described, it is delivered from the machine in such a finely-divided state that it can be immediately ground in oil without the chasing heretofore considered necessary. The pipes *B* are turned very slowly in the pans, so that their feeding action is slow and the lead is gradually dried, so that it is not subjected to such heat as would injure it. The process is, however, much more rapid than the flat drying-pans heretofore employed, and one such apparatus, where the drying-pans are about twenty-five feet long, is adapted to dry from five to ten tons of lead per day, being sufficient for an ordinary lead-manufactory.

In drying flour, clay, and other pulverulent materials in my improved apparatus it is employed in substantially the manner above described, the materials being crushed between the rolls after leaving each drying-pan, and delivered in a finely-divided condition. In drying grain and like substances the rolls are dis-

pensed with, the substances passing from one pan directly to the other, where more than one pan is required.

During the operation of the apparatus all the water of condensation passes from the pipes and rolls into the exhaust-pipes on account of the peculiar construction of their swivel-connections, so that the steam can heat them over their entire surfaces, and there is no opportunity of this water chilling them.

What I claim as my invention, and desire to secure by Letters Patent, is—

1. In apparatus for drying lead and other materials, the combination, with a heated trough and heated pipe provided with a flight or equivalent feeding apparatus, of heated rolls for crushing the material during drying, substantially as set forth. 65

2. In drying apparatus, the combination of two or more drying-troughs supported one above the other, and provided with heated pipes having feeding apparatus, with heated rolls so located as to receive the material from one trough, crush it, and deliver it to the next trough, substantially as and for the purposes set forth. 75

3. In drying apparatus, the combination, with the heated pipe *E*, provided with feeding apparatus *e*, of the heated trough or pipe *B*, provided with the curved supplemental flanges *F*, extending partially over the feeding apparatus in contact therewith, substantially as and for the purposes set forth. 80

4. In drying apparatus, the hollow rolls *C*, so connected by means of a swivel with the steam-exhausts *R* that both the internal and external diameter of the rolls and exhausts are substantially the same, as and for the purposes set forth. 90

5. In drying apparatus, the combination, with the trough or pan *B*, of the pipe *E*, having the flight or equivalent feeding apparatus *e*, and wings *g*, extending longitudinally of the pipe and decreasing in height at their forward ends, substantially as and for the purposes set forth. 95

In testimony whereof I, the said GEORGE L. IRWIN, have hereunto set my hand.

GEORGE L. IRWIN.
